CLAIM

The ornamental design for a protective collar for golf bag, as shown.

DESCRIPTION

FIG. 1 is a side perspective view of the protective collar for a golf bag;

FIG. 2 is a rear elevational view thereof;

FIG. 3 is a front elevational view thereof;

FIG. 4 is a right side view thereof;

FIG. 5 is a left side thereof;

FIG. 6 is a top plan view thereof; and,

FIG. 7 is bottom plan view thereof.

The golf bag, straps, interior cloth lining and handle portion are shown in dashed lines as not forming part of the ornamental features.
